UNITED STATES PATENT OFFICE.

RICHARD M. WILLIAMS, OF SHAWNEE, OKLAHOMA.

GUN ATTACHMENT.

1,266,087.

Specification of Letters Patent. Patented May 14, 1918.

Application filed July 2, 1917. Serial No. 178,146.

To all whom it may concern:

Be it known that I, RICHARD M. WILLIAMS, citizen of the United States of America, residing at Shawnee, in the county 5 of Pottawatomie and State of Oklahoma, have invented certain new and useful Improvements in Gun Attachments, of which the following is a specification, reference being had therein to the accompanying 10 drawing.

This invention has for its principal object the production of a device used for lengthening the barrels of short construction for facilitating greater accuracy in 15 longer shots.

Another object of this invention is the production of a gun attachment wherein a choke or cylindrical bore end is removably mounted upon a short gun barrel for increasing the accuracy of a shot at a longer 20 distance.

A still further object of this invention is the production of a gun attachment wherein simple and efficient locking means is used 25 for positively holding the removable end from being accidentally moved.

A still further object of this invention is the production of a gun attachment wherein the locking means used for holding the removable end from accidental displacement will also adjust the removable end so as to 30 positively and accurately aline the sights.

With these and other objects in view, this invention consists of certain novel combinations, constructions and arrangements of parts as will be hereinafter fully described 35 and claimed.

In the accompanying drawing:

Figure 1 is a side elevation of the gun attachment, showing the same in condition for 40 use.

Fig. 2 is a side elevation of the attachment and lock.

Fig. 3 is a bottom plan view of the device.

Fig. 4 is a longitudinal section through 45 the device.

Fig. 5 is a fragmentary side elevation of the end of the gun barrel showing a portion of the lock carried thereby.

Fig. 6 is a section taken on the line 6-6 50 of Fig. 2.

Fig. 7 is a section taken on the line 7-7 of Fig. 2.

Fig. 8 is a front elevation of the gun attachment. 55

Fig. 9 is a detail perspective view of the locking bar.

Fig. 10 is a fragmentary sectional view through a slightly modified form of the 60 device.

Fig. 11 is a fragmentary sectional view taken at right angles to Fig. 10.

Referring to the accompanying drawing by numerals, it will be seen that the device is used in combination with an ordinary gun as illustrated in general at 1. It is, of course, obvious that if so desired a gun may be provided with an ordinary sight 2. The barrel 3 of the gun 1 may be of any desired length and is provided with a reduced portion 4 which portion 4 is externally threaded as shown at 5 in Fig. 5. When only ordinary shooting is done with the gun or when targets within a medium or close range are fired at, the removable end is not employed. 70 When, however, targets at a greater distance are fired at, the removable end which, of course, may be of any desired length, is then mounted upon the barrel 3. In order to accomplish this function, the removable end 6 80 is hollowed out and internally threaded as indicated at 7 adjacent its inner end. This hollowed out portion is large enough to receive the externally threaded portion of the barrel 3 as shown clearly in Fig. 4 whereby 85 the removable end will be carried upon the end of the gun barrel 3. It is, of course, obvious that it is absolutely necessary to provide an even bore and inner surfaces for the gun barrel and the removable end for 90 permitting the charge to pass freely through the barrel and the removable end without being deflected or caused to lodge at the junction of the barrel and removable end. It will further be seen that the removable 95 end 6 is provided with a sight 8 adjacent its outer portion.

In order to hold the removable end from being accidentally displaced or becoming loose after the gun has been fired a few 100 times, there is provided a lock as will be hereinafter described. A pair of lugs 9 are fixedly mounted upon the gun barrel 3 adjacent the reduced portion thereof and these lugs may be retained in any desired manner 105 such for instance, as being screwed upon the barrel or being shrunk, welded or annealed thereon so as to be permanently retained in a set position spaced from each other as shown in Fig. 3. A locking bar 10 is sub- 110

stantially rectangular in cross section and is indicated as clearly shown in Fig. 9 and has a thickened journal 11 at one end through which extends an opening 12. This journal 11 fits between the lugs 9 so as to permit the pivot pin 13 to pass through the opening 12 and be carried by the lugs 9 for pivotally supporting the locking bar.

A one-piece lug 14 is shrunk or otherwise secured upon the removable end 6 at a distance from the internally threaded portion 7 of the removable end portion, the lug 14 will have a firm support since it is carried upon the thickest part of the removable end 6 as shown in Fig. 4. This lug 14 is provided with a rectangular notch 15 as shown clearly in Fig. 7, this notch being substantially the same size as the lock bar 10 so as to fit snugly upon the locking bar when the same is moved thereinto.

A threaded neck 16 projects from the rectangular body 10 of the locking bar so as to carry the nut 17 when the lock is in operation for positively holding the bar in engagement with the lug 14.

When it is desired to shoot accurately at targets at a great distance, the removable end is secured on to the end of the barrel 3 as shown in Figs. 1 and 4 inclusive. After the removable end has been removed to its correct position, the locking bar pivotally mounted upon the lugs 9, is then swung to pass into the notch 15 of the lug 14 carried upon the removable end 6. It is obvious that the sights 2 and 8 are in alinement with each other when the lock is in a locked position, it is absolutely necessary for the end to be turned so as to have the sights in alinement before the squared or rectangular locking bar can pass into the notch 15 of the lug 14.

Of course, it is not necessary for the operator to aline the sights for the sights are automatically alined by the turning of the removable end to such a position as will allow the locking bar to be moved into the notch of the lug 14. The nut 17 is then screwed on to the externally threaded neck 16 until the nut binds firmly upon the lug 14 as shown in Figs. 1 to 4 inclusive. This action of the nut will positively hold the locking bar against accidental displacement and therefore the locking bar in turn will hold the removable end from becoming loose or accidentally disengaging the barrel 3 of the gun since the lock will hold the attachment against rotating. Furthermore, since the locking bar and nut connect the lugs 14 of the barrel and the removable end, considerable strain or stress caused by the charge passing through the removable ends, will be relieved from the threads of the reduced portion of the gun barrel and the hollowed out portion of the removable end.

By referring to Figs. 10 and 11, it will be seen that a removable end 6' is provided

with a lug 14' having a notch 15'. The locking bar in this modified form is mounted similarly to the preferred form and it is not therefore, deemed necessary to show the pivotal mounting of the locking bar. The locking bar 18 in this modified form is substantially cylindrical of the same size adjacent its free end and is provided with externally threaded ends adjacent its ends. The nut 20 mounted upon the free end of the locking bar 18 is provided with a frusto-conical portion 21 as shown clearly in Fig. 10. After the removable end 6' is mounted upon the barrel in the usual manner and the locking bar swung into the notch of the lug 14' the nut 20 is secured on to the locking bar so as to cause the frusto-conical portion to pass slightly into the notch 15' of the lug 14' which action will not only hold the locking bar 18 in a set position, but owing to the frusto-conical construction of a portion of the nut, the nut will urge the lug 14' in either direction for short distances so as to positively aline the sight of the gun. The operation of this modified form is substantially identical with the operation of the preferred form, excepting instead of having the locking bar rectangular and fitting in a rectangular notch of the lug for automatically alining the sights, a frusto-conical nut 95 is used which nut passes slightly into the lug for causing the sights to be automatically alined.

From the foregoing description, it will be seen that a very efficient gun attachment 100 has been provided which will enable the operator of the gun to hit a target by increased accuracy occasioned by positioning the removable end upon the gun barrel, while simple and efficient locking means has 105 been provided for holding the removable end from accidentally becoming loose, which locking means when being secured for holding the removable end against movement will automatically cause the sights of the 110 gun to be alined.

What is claimed is:

1. In a gun attachment of the class described, the combination of a gun having a barrel, a removable end positioned upon the end of said barrel, lugs carried by said barrel and said removable end, a locking bar pivotally mounted upon a plurality of said lugs, said bar being adapted to be moved into engagement with the remaining lug, and a nut carried upon said locking bar and engaging said last mentioned lug for holding the locking bar in a set position whereby said removable end will be held against accidental displacement. 120

2. In a gun attachment of the class described, the combination of a gun having a barrel, a removable end positioned upon said barrel, said gun and said end having sights, a pair of lugs fixedly mounted upon 125

5 said barrel, a lug fixedly mounted upon said removable end, said last mentioned lug having a rectangular notch, a locking bar pivotally mounted upon said first mentioned lugs, said locking bar having a rectangular body, an externally threaded neck extending from said body, said bar being adapted to be swung so as to pass into the notch of said last mentioned lug whereby 10 said sights will be automatically aligned with each other, and a nut carried upon said threaded neck and bearing upon said last mentioned lug for holding said locking bar against accidental displacement, thereby 15 holding said removable end from accidental movement.

3. In a gun attachment of the class described, the combination of a locking bar having a threaded end, said locking bar being adapted to be supported upon a gun barrel, a lug having a notch formed therein, 20 said lug being adapted to be carried upon a removable end, a nut threaded upon said locking bar, said nut having a frusto-conical portion, said frusto-conical portion being adapted to slightly pass into said lug for alining the sights of the gun and the removable end.

4. In a gun attachment of the class described, the combination of gun having a barrel, a removable end positioned upon said barrel, said gun and end having sights, a locking bar pivotally mounted upon said barrel, a retaining means mounted upon 35 said end and a nut adjustably mounted upon said bar and engaging said means for holding bar in a set position, whereby said end will be held against accidental displacement.

40 5. In a gun attachment of the class described, the combination of a gun having

a barrel, a removable end engaging said barrel, said gun and end having sights, a pair of lugs fixedly mounted upon said barrel, a lug fixedly mounted upon said removable end, said last-mentioned lug having a rectangular notch, a locking bar pivotally mounted upon said first mentioned lugs, said locking bar having a rectangular body, 5 said bar being adapted to be swung so as to pass into the notch of said last mentioned lug, whereby said sights will be aligned with each other, and means for holding said bar in engagement with said last-mentioned lug, whereby said removable end 5 will be held against accidental movement.

6. In a gun attachment of the class described, the combination of a gun having a barrel, a removable end positioned upon the end of said barrel, a locking bar pivotally mounted upon said barrel, a lug carried by said end, said lug having a notch formed therein, said bar fitting snugly within said notch, means for holding said bar in engagement with said lug whereby 6 said removable end will be held against accidental movement in any direction.

7. In a gun attachment of the class described, the combination of a gun having a barrel, a removable end positioned upon the 70 end of said barrel, a locking bar pivotally mounted upon said barrel, a lug carried by said end, said lug having a notch formed therein, said bar fitting snugly within said notch, whereby said removable end will be 75 held from twisting upon said barrel, and a nut mounted upon said bar and bearing upon said lug for holding said bar from accidentally disengaging said lug.

In testimony whereof I hereunto affix my 80 signature.

RICHARD M. WILLIAMS.
